POCKETBOOK

William R. Galter, Chicago, Ill.

Application January 9, 1950, Serial No. 7,101

Term of patent 3½ years

(Cl. D87—3)

To all whom it may concern:

Be it known that I, William R. Galter, a citizen of the United States of America, residing at 159 East Ohio Street, Chicago, Illinois, have invented a new, original, and ornamental Design for a Pocketbook, of which the following is a specification, reference being made to the accompanying drawing forming part hereof.

Referring to the drawing, Fig. 1 is a front elevational view of a pocketbook embodying my new design; Fig. 2 is a side elevational view thereof taken from the left of Fig. 1; Fig. 3 is a rear elevational view of the pocketbook; and Fig. 4 is a side elevational view thereof taken from the left of Fig. 1.

I claim:

The ornamental design for a pocketbook, substantially as shown.

WILLIAM R. GALTER.
